CONVERTIBLE CHAIR-BED

Angelo R. Paladino, Elmont, N. Y., assignor to
The Englander Company, Inc., Chicago, Ill., a
corporation of Delaware

Application March 4, 1947, Serial No. 732,258

4 Claims. (Cl. 155—47)

1

This invention relates to convertible chairs and the same has particular reference to a chair having a foldable frame forming the seat and back rest thereof and which may be extended to form a bed.

The invention comprehends a folding frame embodying a plurality of sections which are hinged together and to the chair for movement thereof from an extended position forming a full length bed to a collapsed position in which one of the sections constitutes the chair seat and the other sections form the back rest.

The invention has for a further object, the provision of a folding frame of said character in which the seat forming section is mounted for movement to an inclined position to thereby provide a raised end when serving as a bed.

With the foregoing and other objects in view, reference is now made to the following specification and accompanying drawings in which the preferred embodiment of the invention is illustrated.

In the drawings:

Fig. 1 is a top plan view of a chair provided with a foldable frame constructed in accordance with the invention and illustrating the same in extended bed forming position with the cushions removed.

Fig. 2 is a side view thereof.

Fig. 3 is a side view of the chair with the foldable frame shown in partially collapsed relation.

Fig. 4 is a side view of the chair with the foldable frame collapsed and secured in chair forming position.

Fig. 5 is a front view of the chair showing the seat rest in elevated position.

Referring to the drawings by character of reference, the chair includes a frame 10 having legs 11 secured thereto at the opposite ends thereof and which legs extend upwardly above the frame and have arm rests 12 secured to the upper ends thereof.

The chair also includes a foldable frame indicated generally by the reference character 13 which consists of end frame sections 14 and 15 at the opposite ends thereof and an intermediate frame section 16 hingedly connected by pivot pins 17 with the end section 15 and by pivot pins 18 with a metal frame 19 located between the chair frame 10 and the forward frame section 14.

The end section 15 comprises spaced parallel side rails 20 and an end rail 21 connected between the side rails at the outer ends thereof which rails are of angle iron construction and are arranged with the horizontal flanges 22 disposed

2

uppermost and the vertical flanges 23 disposed outwardly. The end rail 21 and the side rails 20 are reinforced by diagonally extending bracing straps 24 riveted to the upper horizontal flanges thereof adjacent the opposite ends of the end rail 21. An angle bar 25 is secured to the end rail 21 with the horizontal flange 26 thereof extending outwardly for engagement with the keeper members 27 for retaining the end section 15 and the intermediate section 16 in latched engagement to form a back rest when the foldable frame 13 is disposed in collapsed chair forming position. The end section 15 also includes leg members 28 and 29 located adjacent the opposite ends of the side rails 20 and which are pivoted at their upper ends by the pivot pins 31 to the vertical flanges 23 thereof. The legs 28 and 29 are provided with caster rollers 32 and have link members 33 pivoted thereto at their opposite ends on pivot pins 34. Between the pivotal connections of the links 33 with the legs 28 and the caster rollers 32 thereof link members 35 are pivotally connected to said legs 28 on pivot pins 36, the opposite ends of the link members 35 being pivotally connected to the intermediate frame section 16 for swinging movement of the legs 28 and 29 to a retracted position between the end section 15 and the intermediate section 16 when the said sections are moved into latched relation to form the back rest for the chair.

The intermediate section 16 includes parallel side rails 38 which are of angle iron construction and are arranged with their horizontal flanges 39 uppermost and with their vertical flanges 40 disposed outwardly and pivotally connected at their outer ends to the vertical flanges 23 of the end section 15 by the pivot pins 41. The intermediate section 16 also includes an end rail 41 which is connected between the side rails 38 adjacent the pivotal connection of the side rails with the metal frame 19, the said section being reinforced by diagonally extending bracing strips 42 riveted at their opposite ends to the horizontal flanges 39 of the side rail 38 and to the end rail 41 adjacent its opposite ends.

The metal frame 19 is similarly of angle iron construction and includes opposite side rails 44 and an end rail 45 connected between the outer ends of the side rails which side and end rails are arranged with their horizontal flanges 46 disposed uppermost and with their vertical rails 47 disposed outwardly and secured against the inner face of the chair frame 10. The intermediate section 16 is pivotally connected to the vertical flanges 47 of the metal frame 19 by the

pivot pins 18 and adjacent said pivotal connection the metal frame 19 is provided with leg members 48 secured to the side rails 47 by rivets 49 which leg members have caster rollers 50 at the lower ends thereof and are connected by a transversely extending bar 51, on which bar the keeper members 27 are mounted.

The end section 14 is of angle iron construction and includes opposite side rails 52 and an end rail 53 connected between the side rails at the forward ends thereof and which have their horizontal and vertical flanges disposed uppermost and outwardly respectively and arranged within the metal frame 19 to which the side rails 52 are pivotally connected on pivot pins 54 for movement of the said section from a horizontal seat forming relation to an inclined relation as shown in Fig. 2 when the end section 15 and the intermediate section 16 are disposed in aligned bed forming relation. The side rails 52 and end rail 53 of the seat forming section 14 rest upon angulated bars 56 secured at their opposite ends to the metal frame 19 for supporting the section 14 in seat forming relation. The angle bars 56 are provided with a series of longitudinally spaced notches 57 which open through the upper edges thereof for selectively receiving the transversely extending bight portion 59 of a U-shaped yoke 60 pivoted to the side rails of the end section 14 for selectively supporting the same in an inclined relation.

A wire mesh spring 62 of any desired construction is connected with the foldable frame 13 between the side and end rails of the end and intermediate sections 14, 15 and 16 for supporting mattress sections thereon (not shown) and which wire mesh spring is adapted to be folded with the folding of the end and intermediate sections 15 and 16 to upright relation to form the back rest for the chair.

When the foldable frame 13 is in chair formation and the same is to be extended into bed forming relation the mattress sections are removed and the end and intermediate sections 15 and 16 are rocked forwardly on the pivot pins 18 to free the angle bar 25 from engagement with the keeper members 27. The end section 15 is then swung rearwardly on the pivot pins 17 into longitudinal horizontal alignment with the seat forming section 14 whereby the link members 33 and 35 swing the leg members 28 and 29 from a collapsed position between the end section 15 and intermediate section 16 to an upright bed supporting relation as shown in Fig. 2. If desired, the seat forming section 14 may then be elevated by engagement of the yoke 60 with the desired notches 58. The cushion sections may then be disposed upon the folding frame 13 to cover the wire mesh spring.

What is claimed is:

1. In a convertible chair, a chair frame, an angle bar frame secured to the inner face of the chair frame, a seat forming frame section pivoted to the angle bar frame adjacent the rear thereof for movement of the seat forming frame section to inclined relation, an end frame section having pivotally connected leg members at the opposite ends thereof, an intermediate frame section pivotally connected at its opposite ends with the angle bar frame and end frame section respectively for swinging movement from aligned bed forming relation with the seat forming frame to collapsed relation in which the intermediate and end frame sections are arranged upright to constitute the back rest of the chair, interengag-

ing means carried by the end frame section and the angle bar frame for latching the intermediate and end frame sections in upright back rest forming relation and link members connecting the leg members and the intermediate section for movement of the leg members into collapsed relation between the intermediate and end frame section with the movement thereof into back rest forming relation.

10. 2. In a convertible chair, a chair frame, a foldable metal frame including a rigid frame section rigidly affixed to the chair frame and front and rear frame sections and an intermediate frame section hingedly connected with the rear frame section and with the rigid frame section, said front frame section being supported by said rigid frame section and forming the seat frame of the chair, said intermediate and rear frame sections forming the back rest frames of the chair and being swingable on their pivotal connections to longitudinally aligned bed forming relation, leg members secured to said rigid frame section adjacent the rear thereof, leg members secured to said rear frame section at the opposite ends thereof, link members pivotally connected with the front and rear leg members of the rear frame section and link members pivotally connected with the intermediate frame section and the front legs of said rear frame section for swinging movement of said front and rear leg members with the rear frame section to collapsed relation between the intermediate and rear frame sections when the same are arranged in back rest forming position and interengageable means carried by said rear frame section and the leg members of the rigid frame section for latching the intermediate and rear frame sections in back rest forming position.

3. In a convertible chair, a chair frame, a foldable metal frame including a rigid frame section rigidly affixed to the chair frame and front and rear frame sections and an intermediate frame section hingedly connected with the rear frame section and with the rigid frame section, said front frame section being supported by said rigid frame section and forming the seat frame of the chair, said intermediate and rear frame sections forming the back rest frames of the chair and being swingable on their pivotal connections to longitudinally aligned bed forming relation, leg members secured to said rigid frame section adjacent the rear thereof, leg members secured to said rear frame section at the opposite ends thereof, link members pivotally connected with the front and rear leg members of the rear frame section and link members pivotally connected with the intermediate frame section and the front legs of said rear frame section for swinging movement of said front and rear leg members with the rear frame section to collapsed relation between the intermediate and rear frame sections when the same are arranged in back rest forming position, interengageable means carried by said rear frame section and the leg members of the rigid frame section for latching the intermediate and rear frame sections in back rest forming position, a bale member pivoted to said front frame section and notched bars carried by said rigid frame section for engagement of the bale in the said notches for supporting the front frame section in inclined relation when the rear and intermediate frame sections are in bed forming relation.

4. In a convertible chair, a chair frame, a foldable metal frame including a rigid frame section

rigidly affixed to the chair frame and front and rear frame sections and an intermediate frame section hingedly connected with the rear frame section and with the rigid frame section, said front frame section being supported by said rigid frame section and forming the seat frame of the chair, said intermediate and rear frame sections forming the back rest frames of the chair and being swingable on their pivotal connections to longitudinally aligned bed forming relation, leg members secured to said rigid frame section adjacent the rear thereof, leg members secured to said rear frame section at the opposite ends thereof, link members pivotally connected with the front and rear leg members of the rear frame section and link members pivotally connected with the intermediate frame section and the front legs of said rear frame section for swinging movement of said front and rear leg members with the rear frame section to collapsed relation between the intermediate and rear frame sections when the same are arranged in back rest forming position, said rear frame section having a trans-

versely extending outwardly projecting bar secured thereto at the outer end thereof and said rigid frame section having rearwardly projecting latch elements adapted to receive the said bar for supporting and latching the intermediate and rear frame sections in upright back rest forming relation.

ANGELO R. PALADINO.
